UNITED STATES PATENT OFFICE

PARDEE H. FRANK, OF CANTON, OHIO, ASSIGNOR TO THE TIMKEN ROLLER BEARING COMPANY, OF CANTON, OHIO, A CORPORATION OF OHIO

ROLLING MILL

Application filed March 9, 1928. Serial No. 280,327.

My invention relates to rolling mills of the kind wherein backing or supporting rolls are used to relieve the pressure on the working rolls. The principal objects of 5 the invention are to reduce the weight of the backing rolls, to prevent excessive heating thereof, to minimize cross-bending stresses thereon, to reduce friction and provide for the adjustment 10 of bearings, and to simplify and cheapen repair and replacement of the backing rolls. The invention consists principally in making the backing roll hollow and mounting it on roller bearings interposed between it 15 and a support extending therethrough. It also consists in the parts and in the combinations and arrangements of parts herein-after described and claimed.

In the accompanying drawing, wherein 20 like numerals refer to like parts wherever they occur,

Fig. 1 is a vertical view partly in section and partly in elevation of a four high rolling mill embodying my invention, and

Fig. 2 is an enlarged vertical longitudinal section through one of the housings for the ends of the working rolls, showing the roller bearings interposed between the neck at one end of a working roll and the housing 30 ing therefor.

The ordinary four high rolling mill comprises a pair of rolls 2 arranged one above the other and a backing roll 1 for each working roll, the axes of all of the rolls being 35 in the same vertical plane. In the construction illustrated, the working rolls have necks 3 that are provided with roller bearings (hereinafter described) that are interposed between said necks and the housings 4 that 40 are secured to the end members 5 of the framework of the mill.

The upper and lower backing rolls 1 are similar to each other in construction. Each backing roll 1 comprises a heavy cylindrical 45 shell 6 preferably of about the same length as the working rolls 2. Each of said shells is supported by a shaft or beam 7 that extends through said shell and has its ends rigidly supported in boxes 8 that are mounted in the end frames 5 and are adapted to

slide vertically in guideways on said end frames sufficiently for purposes of adjustment. The upper surface of each of the top boxes is provided with a socket or recess in which bears a heavy adjusting screw 9 that 55 works in a screwthreaded hole provided therefor in the frame. Between the shell 6, that constitutes the backing roll 1, and the beam or shaft 7, that constitutes the support therefor, are interposed series of roller bearings (hereinafter described) that enable the backing roll to rotate on its axis. In practice, the supporting beam is adjusted, by means of said screws and boxes, so that the backing roll 1 will contact with the working roll 2 throughout the full length thereof. 65

The bearing construction for the necks 3 of the working rolls 2 comprises two circular series of conical rollers 10 with their cones or inner bearing members 11 and their 70 cups or outer bearing members 12, the cones 11 being mounted on the roll necks 3 and the cups 12 being mounted in the housings 4. The cones 11 on each neck 3 are arranged with their large ends toward each other but 75 separated by a spacing member in the form of a sleeve 13 slidable on the roll neck. The small end of the inner cone bears against a ring 14 provided therefor on the roll neck and itself bearing against a shoulder on the 80 working roll. The innermost cup or outer bearing member has its large end bearing against a flange 15 provided therefor on the inner end of the housing. The outer or endmost cup has a sliding fit in the outer end 85 of the housing and bears against an annular rib 16a provided therefor on a closure plate 16 that is secured to the end of said housing, as by means of cap screws 17, shims 18 being interposed between said closure plate and the 90 end of the housing to provide for the adjustment of the bearings. The same construction is used at the opposite end of the working roll.

By this arrangement the bearings of the 95 working roll neck may be easily and accurately adjusted. For instance, if the bearings wear, it is only necessary to remove the closure cap 16 and one or more shims 17, and then replace such cap. In tightening the cap 100

16, the flange 16a thereof bears against the end of the outer cup 12, which is thereby moved endwise and such movement is transmitted through the antifriction rollers 10 of 5 the outer bearing to the outer cone 11 and thence through the sleeve 13 to the inner cone and the rollers associated therewith.

The bearing construction of the backing roll comprises a plurality of series of conical 10 roller bearings. In the construction shown, there is a duplex or reversely tapered cone 20 mounted with a sliding fit on the shaft or supporting beam near each end of the roll, such reversely tapered cone having conical 15 bearing surfaces tapering from the middle toward each end and having the usual thrust rib 21 near the middle thereof. A circular series of rollers 22 is mounted on each bearing surface of said duplex cone and each series 20 of rollers cooperates with a cup or outer bearing member 23 that has a sliding fit in the end portion of said shell or backing roll. In the construction shown, two such duplex cones 24 are slidably mounted on the shaft or supporting beam 7 near the middle of the backing roll, and series of rollers 25 are provided 25 for the respective conical bearing surfaces of said duplex cones, and bearing cups 26 for the respective series of rollers are slidably mounted in said backing roll. The cups are spaced apart by slideable sleeves 27 that bear against the ends thereof. At each end of the backing roll, a closure plate 28 is secured thereto as by cap screws 29, with shims 30 interposed 30 between the end of the closure plate and the end of the backing roll. On each closure plate 28 is an annular flange or rib 31 arranged to bear against the outermost bearing cup in said backing roll. It is obvious from this arrangement that the endwise movement of the closure plate has the effect of adjusting all of 35 the conical bearings.

In the construction shown, a passageway 32 extends from each end of the supporting beam or shaft 7 longitudinally and thence laterally and opens into the space between the shaft and the backing roll, thus affording an easy and efficient way of lubricating the bearings. The ends of said passageway are provided with plugs 33 that have threaded engagement with the shaft. Any suitable means may be used at the ends of the roller for sealing the annular space between said roller and the shaft so as to prevent the 45 escape of lubricant therethrough. If desired, oil may be circulated continuously through the shaft and bearings, being admitted at one end and let out at the other, thus serving both to lubricate the bearings 50 and carry off heat. Likewise, the shaft may have a separate passageway for a cooling liquid independent of the lubricating system.

Among the principal advantages of this 55 construction are the following: On account

of the use of roller bearings, friction is greatly reduced. As the shell alone rotates and the shaft or supporting beam remains stationary, less power is required to move the backing roll. On account of the large diameter of the bearing cups, and the multiplicity of series of rollers, and the provision for lubrication, and the freedom of heat radiation, the danger and the disadvantages of overheating the bearings are substantially eliminated. Likewise, on account of the heavy shell being supported at close intervals throughout its length and making contact with the working roll throughout its length, the construction is very effective in preventing any cross bending of the working rolls, which may therefore be made of smaller diameter than would otherwise be practicable. Besides, the bearings are adjustable very easily, and the backing roll may be dismounted merely by sliding the supporting beam out of it by movement endwise.

What I claim is:

1. A rolling mill comprising end frames having housings, working rolls having necks, roller bearings interposed between said necks and said housings, the working surface of said rolls extending nearly the full distance between housings of opposite end frames, a hollow backing roll for each working roll of substantially the same length as the working roll, a rigid beam extending through each backing roll and mounted on said framework, and a plurality of roller bearings having inner and outer bearing members interposed between said beam and said backing roll near the middle and at the ends thereof, the inner members of said bearings fitting freely on said beam and the outer members of said bearings fitting freely in said backing roll, whereby said bearings may be adjusted and said roller may be dismounted by sliding said beam endwise.

2. A rolling mill comprising end frames having housings, working rolls having necks, roller bearings interposed between said necks and said housings, the working surface of said rolls extending nearly the full distance between housings of opposite end frames, a hollow backing roll for each working roll of substantially the same length as the working roll, a rigid beam extending through each backing roll and mounted on said framework, and a plurality of axially movable roller bearings interposed between said beam and said backing roll near the middle and at ends thereof, each bearing comprising an inner bearing member mounted on said beam, an outer bearing member slideable in said bearing roll, antifriction rollers between said inner and outer bearing members, spacing members between said outer bearing members, the fit of said inner bearing members on said beam and of the outer bearing members in said backing roll being free enough

to permit said members to be moved axially and means for locking said outer bearing members in adjusted position.

3. A rolling mill comprising end frames having housings, working rolls having necks, roller bearings interposed between said necks and said housings, the working surface of said rolls extending nearly the full distance between housings of opposite end frames, a hollow backing roll for each working roll of substantially the same length as the working roll, a rigid beam extending through each backing roll and mounted on said framework, and a plurality of roller bearings interposed between said beam and said backing roll near the middle and ends thereof, each bearing comprising an inner bearing member mounted on said beam, and outer bearing member mounted in said bearing roll, antifriction rollers between said inner and outer bearing members, spacing members between said outer bearing members, the fit of said inner bearing members on said beam and of the outer bearing members in said backing roll being free enough to permit said members to be moved axially and means for locking said outer bearing members in adjusted position, said means comprising closure caps removably fastened on the ends of said roller and having annular ribs arranged to bear against the endmost outer bearing members.

4. A rolling mill comprising end frames having housings, working rolls having necks, roller bearings interposed between said necks and said housings, the working surface of said rolls extending nearly the full distance between housings of opposite end frames, a hollow backing roll for each working roll of substantially the same length as the working roll, a rigid beam extending through each backing roll and mounted on said framework, and a plurality of roller bearings interposed between said beam and said backing roll near the middle and ends thereof, each bearing comprising an inner bearing member mounted on said beam and having reversely conical bearing surfaces tapering towards its ends, a series of taper rollers for each of said bearing surfaces, and an outer bearing member for each series of rollers mounted in said backing roll, spacing sleeves between the large ends of said outer bearing member, the fit of said inner bearing members on said beam and of the outer bearing members in said backing roll being free enough to permit said members to be moved axially and means for adjusting said bearings endwise.

5. A rolling mill comprising end frames having housings, working rolls having necks, roller bearings interposed between said necks and said housings, the working surface of said rolls extending nearly the full distance between housings of opposite end frames, a hollow backing roll for each working roll of

substantially the same length as the working roll, a rigid beam extending through each backing roll and mounted on said framework, and a plurality of roller bearings interposed between said beam and said backing roll near the middle thereof and roller bearings interposed between said beam and said backing roll at each end thereof, each bearing comprising an inner bearing member 70 slidable on said beam and having reversely conical bearing surfaces tapering towards its ends, a series of taper rollers for each of said bearing surfaces, and an outer bearing member for each series of rollers slidable in said backing roll, spacing sleeves between the 75 large ends of the outer bearing members of the endmost bearings and the large ends of the nearest outer bearing members of the middle bearings, and means at the ends of the 80 said backing roll for adjusting said bearings 85 endwise.

6. A rolling mill comprising end frames having housings, working rolls having necks, roller bearings interposed between said necks and said housings, the working surface of said rolls extending nearly the full distance between housings of opposite end frames, a hollow backing roll for each working roll of substantially the same length as the working roll, a rigid beam extending through each backing roll and mounted on said framework and having a passageway extending from an end thereof and opening through its side into the space between said backing roll and said beam, and a plurality of roller bearings interposed between said beam and said backing roll near the middle and at the ends thereof, each bearing comprising an inner bearing member mounted on said beam, an outer bearing member mounted in said bearing roll, antifriction rollers between said inner and outer bearing members, spacing members between said outer bearing members, the fit of said inner bearing members on said beam and of the outer bearing members in said backing roll being free enough to permit said members to be moved axially and means for locking said outer bearing members in adjusted position.

Signed at Canton, Ohio, this 5th day of March, 1928.
